UNITED STATES PATENT OFFICE.

JOSEPH A. PITNER, OF MINOT, NORTH DAKOTA.

PLOW.

1,191,459.

Specification of Letters Patent. Patented July 18, 1916.

Application filed June 3, 1915. Serial No. 31,980.

To all whom it may concern:

Be it known that I, JOSEPH A. PITNER, a citizen of the United States, residing at Minot, in the county of Ward, State of North Dakota, have invented certain new and useful Improvements in Plows; and I do hereby declare the following to be a full, clear, and exact description of the invention, such as will enable others skilled in the art to which it appertains to make and use the same.

The present invention is directed to improvements in plows, and has for its object to provide a device of this character with a point which can be easily and quickly removed or replaced without the aid of bolts.

A further object of the invention is to provide a plow having a removable point which when worn may be replaced by a new one easily and quickly without requiring the use of bolts.

With these and other objects in view, this invention resides in the novel features of construction, formation, combination and arrangement of parts to be hereinafter more fully described, claimed and illustrated in the accompanying drawing, in which:

Figure 1 is a perspective view of the device. Fig. 2 is a rear elevation of the same. Fig. 3 is an inverted plan view. Fig. 4 is a sectional view on line 4—4 of Fig. 3. Fig. 5 is a side elevation. Fig. 6 is a sectional view on line 6—6 of Fig. 3.

Referring to the drawing 1 designates the mold-board, and 2 the land side, said mold-board and land side being connected near their upper ends by a brace bar 3. The land side is provided with the usual frog 4, which is bolted to the mold-board 1, said frog having its lower edge provided with lugs 5 and 6, the latter lug having a fin 7, the purpose of which will appear later. The mold-board is provided at its lower edge with an extension 8, and spaced from the extension 8 is a recess 9.

The share 9' is provided with an integral point 10 which is provided at its upper edge with a finger 11, said point being further provided with a thickened portion 12 in which is formed a socket 13, said socket being slightly tapered to correspond to the tapered formation of the extension 6. Opening into the socket 13 is a groove 14, which is adapted to receive the fin 7 when

the extension 6 is engaged in the socket, 55 and at which time the finger 11 engages the recess 9 and the lugs 5 and 8 engage the rear side of the point, as clearly shown in Fig. 3 of the drawing.

To hold the share 9' and mold-board 1 in 60 interlocked relation a hook 15 is provided, said hook consisting of sections 16 and 17, which are screw threaded and have their adjacent ends adjustably connected by the nut 18, and since the sections 16 and 17 are oppositely threaded it is obvious that rotation of the nut 18 will cause the hook 15 to be lengthened or shortened. The section 16 of the shank is pivotally connected to the hook 19 which is bolted to the inner surface of 70 the share, while the bill 20 of the section 17 is engaged in the perforation 21 formed in the plate 22, said plate being fixed to the mold-board 1. Thus it will be seen that the shank of the hook can be lengthened so as 75 to remove the bill from the perforated plate, and when it is desired to replace the point it is only necessary to place the bill in engagement with the plate and rotate the nut 18, whereupon the sections 16 and 17 will be 80 drawn toward each other, thus firmly interlocking the point and mold-board.

Relative lateral movement of a point and mold-board is prevented by the lugs.

What is claimed is:—

In a plow, the combination with a mold-board, a share having a socket, a groove formed therein, lugs carried by the mold-board, one of said lugs being detachably engaged in said socket and having a fin for 90 engaging said groove, the remaining lugs being engaged with one face of the share, a hook carried by the share, a perforated plate carried by the mold-board, a hook consisting of adjustably connected sections, one of said 95 sections being pivotally and removably engaged with the first named hook, a bill carried by the other section of the hook and being adapted to removably engage the perforation of the plate, said second named 100 hook serving to hold the share and mold-board in interlocked relation.

In testimony whereof, I affix my signature, in the presence of two witnesses.

JOSEPH A. PITNER.
